HARRY SLATER, OF METHUEN, MASSACHUSETTS.

BEARING FOR HIGH-SPEED FLIERS.

1,369,908.

Specification of Letters Patent. Patented Mar. 1, 1921.

Application filed July 12, 1920. Serial No. 395,710.

To all whom it may concern:

Be it known that I, HARRY SLATER, a citizen of Great Britain, residing at Methuen, in the county of Essex and State of Massachusetts, have invented certain new and useful Improvements in Bearings for High-Speed Fliers, of which the following is a specification.

This invention relates to bearings for textile machines or frames for spinning roving, of what are known as the flier type. It is applicable specifically to certain types of fliers, and its purpose is to provide means whereby a higher speed can be obtained, and therefore greater production, without injury to the machine.

In the type of machines to which my device is especially applicable, there are a plurality, generally a large number, of spindles each carried near its bottom in suitable bearings in the frame and connected by suitable belts or cords, so that the spindles can be revolved at high speed. The flier consists of two arms connected together and terminating in a tubular neck, which is slipped over the top end of a spindle in such manner that it will be carried thereby and will revolve therewith.

I am well aware that in certain types of Gill boxes and drawing boxes, the top end of the spindle is carried in closed bearings, but with such bearings the process of doffing is slow, and the use of such bearings has been found impractical on flier frames, where there are a large number of spindles, as, for instance, from 24 to 200 on each frame.

My device is peculiarly useful in connection with what is known as the Dandy rover, where the delivery point of the delivery rolls is directly over the top of the spindle and the center of the tubular neck of the flier, and in flier spinning frames, where the rolls are not directly over the spindle but where, as now in use, what is known as a fly board carrying guide eyes each of which is directly over the center of the spindle, is used.

I have discovered that by making the neck of the flier of such form and of such length on the outside that it can be guided or steadied by a bearing open at the front or the side, the speed can be greatly increased and the production also increased. On new fliers, the neck can be made of suitable

length and shape, and on old fliers I can sweat or force on the neck a thimble which will coöperate with the top bearing.

In order to doff, that is, remove the fliers and bobbins on such frames, it is merely necessary, in the Dandy rover, to swing out the tops of the spindles simultaneously in a curve which is substantially horizontal, to free the necks from the bearings or, in other types of frames, it is merely necessary to move the bearings away from the necks, preferably simultaneously, as these parts are not locked together in any way.

In the construction where I move the bearings away from the fliers, I find that, by a slight modification of the bearings, the fly board can be dispensed with.

My invention consists primarily in so forming the neck of a flier, as distinguished from a spindle, that it can be guided by a bearing open at the front side or at another side, such neck and bearing being so arranged that they can be separated in a substantially horizontal direction.

In the drawings, Figure 1 is an elevation partly in section showing a single spindle and flier of a frame for working textiles of the Dandy rover flier type, wherein the top of the spindle and flier can be swung out in a well known manner.

Fig. 2 is a view similar to Fig. 1 of a single spindle and flier of another type of frame, wherein the spindle is revoluble but does not swing out.

Fig. 3 is an enlarged plan view of the top of a flier and bearing embodying my invention, as shown in Figs. 1 and 4.

Fig. 4 is a sectional elevation on line 4—4 of Fig. 3.

Fig. 5 is an enlarged elevation of the top of the flier, its bearing, and carrier arm, the supporting brackets and beam, with the operating shaft and one gear.

Fig. 6 is a plan view showing a section of carrier rail with its carrier arms and bearings.

Fig. 7 is a detail in elevation showing an alternative method of operating carrier arms.

Fig. 8 is a sectional elevation of the neck of a flier in which the neck is one piece.

Fig. 9 is a plan view showing another method of arranging bearings to be movable horizontally away from the neck of the flier.

In Fig. 1, A indicates a frame for working textiles of the Dandy rover type, having a rail C and other parts in common use. S represents a spindle, carried at the bottom 5 in bearings 10 which form part of said frame, such bearings being supported by the rail 8 carried by rollers, such as 11, which run on tracks, such as 9, in a well known manner. The whirl, such as 13, intermediate rail 12, the lifter rail 14 and the spool 15, are all of a well known type. Each spindle carries at the top a flier F for the roving R which is delivered by rollers 33 and 34. The spindles, spools, and fliers are all 15 arranged so that they can be tipped, thus swinging the necks 22 as well as the arms 20 and 21 of the fliers outward in a substantially horizontal direction.

As shown in Fig. 4, the top end of each 20 spindle S is slotted at 16 to embrace a pin, such as 23, passed through the neck 22 of the flier. Each neck has roving eyes 24 and 25 which preferably are elongated as shown. I also prefer to insert at the top a smaller 25 roving eye 26 to keep the roving in the center.

In making over old fliers, I prefer to sweat or drive on to neck 22 a tubular thimble, such as E, having at the bottom a rounded skirt 30 forming an annular channel 31 which will catch and retain any excess of oil. The outside of this tubular thimble E is true and cylindrical, adapted to revolve at high speed with the spindle and flier.

To coöperate with the neck of the flier carried by a spindle of this type, I prefer to use fixed bearings H open at the front 43 to allow the neck or the thimble E to slip in and to be guided thereby. As shown, for each 40 spindle I attach a bracket K, which has a downwardly projecting arm 53, by means of a cap-screw 55 passing through enlarged slot 54 to the rail C. This bracket K has a horizontal arm 50 and an adjusting slot 51 45 through which, and through slot 47 in a corresponding arm 48 of a bearing H, a bolt, such as 52, passes. Therefore the bearing H is adjustable vertically and horizontally.

Referring to Fig. 3, the bearing H is enlarged into a head in which is a slot 40 which is preferably slightly tapering to receive the bearing member 41, which may be of bronze or any other suitable anti-friction material, rounded at the back 42 to fit snugly 55 on the neck or thimble of the flier, and open at the front 43 whereby it can be swung out without removing any bolts or latches. I prefer to arrange an oil well 44 in the head of the bearing, and to bore a small oil hole 60 45 therefrom so as to reach the neck or thimble, and preferably in this I insert a wick 46 to carry the oil gradually between the bearing surfaces.

In the construction shown in Fig. 2, B 65 represents the frame of a flier spinning

frame similar in most respects to that shown in Fig. 1 except that the spindle T is carried near the bottom in bearings 120 carried by the frame, and also in bearings 121 somewhat higher up. It has the whirl 13 and lifter rail 14, while the bobbin 122 is shown as having no head, and the feed rollers 33 and 34 are set back so that the delivery for the yarn 124 is not directly over the spindle.

In this case, as the spindles do not swing out, I provide that their bearings shall be capable of being moved back away from them in a substantially horizontal direction. To accomplish this I prefer to arrange these bearings in sections of six or eight, as indicated in Fig. 6. For each section, I provide two brackets L, L, one at each end, fixed to the rail C as by screws 59 and each having bearing 60 for an operating shaft 61 which may extend the entire width of the machine. This shaft can be operated by a handle 127 shown in Fig. 6, and, for each section, carries near each end thereof a gear 62. Each bracket L has an upward extension 63 with a passage 64 which serves as a bearing for a carrier arm 70 having rack teeth 71 at the bottom, each set of teeth engaging a gear 62.

Bolted to the top of each pair of toothed carrier arms is a bearing carrier rail 65, and to this are adjustably bolted the open front side bearings M. Each such bearing is open at the front 73 and shaped at the back to guide the tubular neck or thimble, such as E, of a flier. It will be readily seen that, by turning the handle 127, the various gears 62 operating on racks 71 of carrier arms 70 will move the bearing rails 65 and the bearings M carried thereby back and forth so that when it is desired to doff, they can all be moved back out of the way, as indicated by the dotted lines in Figs. 5 and 6.

I find that I can dispense with the fly board generally used to direct the yarn from the delivery rolls to a point directly over the spindles by making the head 66 of each bearing M extend upwardly and over, and inserting in the top thereof, directly over the center of the spindle when the bearing is in position, an open sided eye, such as 68, which may be of porcelain if desired. The upper 115 part of the top of the head is open at 67 so that the bearings can be moved back or forward without breaking the yarn. In order to lock the parts in place I may use a set screw shown at 76.

Instead of using a rack and gear, as shown in Fig. 5, I may, as shown in Fig. 7, use carrier arms 80, each having two depending legs 81 and 82 between which is an eccentric 83 mounted on shaft 61.

In Fig. 8, I show a flier F made with a neck 90 which extends upwardly at 91 a greater distance than is customary in such cases, having roving eyes 95, oil skirt 93, and rounded bottom 92, together with a top eye 130

94. It is obvious that whether a thimble, which may be in the nature of a bushing, such as E, is used, or a neck suitably made in the first place, as shown in Fig. 8, the 5 principle is the same.

My bearing may be open at the front side, as shown in Figs. 1 to 6, or, as shown in Fig. 9, at the side. In this case, the spindle is not capable of being swung outwardly 10 but each bearing U comprises a head 99 open at the side 101 to receive thimble E, and pivoted to the rail C at 100. It is also pivoted at 102 to operating bar 103 which 15 extends the width of the machine. By moving this bar 103 back and forth, bearing U is engaged and disengaged from the flier neck.

It is evident that whether a thimble is used on the neck or the neck is so formed 20 as to serve the same purpose, the principle is the same, and it is evident that whether the opening in my bearing is at the front side, the right side, or the left side, the principle is the same. As the pull of the bands 25 on the whirls is from the back, I prefer to have the open part of the bearing on the front side, however.

The type of spindle in connection with which I use my invention is that wherein 30 the top is free to receive a flier, the bearings being near the bottom end of the spindle. When I speak of the flier or flier neck and 35 bearings being horizontally separable, I include any slight curve, such as that which the flier neck takes at the start, as shown in Fig. 1, or the bearing takes, as shown in Fig. 9.

I claim:

1. The combination in a flier spinning 40 frame having a plurality of revoluble spindles the tops of which are adapted to swing out, of fliers each carried by a spindle and each having at the top a tubular neck with a roving eye, and a tubular thimble having 45 a rounded edge and a skirt at the bottom fitted over said neck and roving eye, with adjustable brackets carried by said frame, and a top bearing each carried by a bracket

one for each neck, each bearing being open at one side and adapted to receive and serve 50 as a top bearing for a thimble carried by a flier.

2. The combination in a flier spinning frame having a plurality of revoluble spindles the tops of which are adapted to swing 55 out, of fliers each carried by a spindle and each having at the top a tubular neck with a roving eye, with a top bearing for each neck each bearing being open at one side and adapted to receive and serve as a top 60 bearing for the neck of a flier.

3. The combination in a flier spinning frame having a plurality of spindles each carried near its lower end by bearings in said frame, of fliers each having a tubular neck 65 with a roving passage therein and each carried by the top of a spindle and revoluble therewith, with a plurality of bearings carried by said frame each bearing being open at one side and adapted to receive and serve 70 as a top bearing for the neck of a flier, said necks and bearings being simultaneously horizontally separable from each other.

4. The combination in a frame for working textiles, of a vertical spindle carried 75 near its lower end by bearings therein and revoluble at high speed, with a flier having a tubular neck carried by the top of the spindle and revoluble therewith, and a bearing open at one side for said neck and also 80 carried by the frame, said neck and bearing being separable horizontally one from the other.

5. The combination in a frame for working textiles, of a spindle carried near its 85 lower end by bearings therein and revoluble at high speed, with a flier having a tubular neck carried by the top of the spindle and revoluble therewith, and a bearing for said neck open at one side and also carried by 90 the frame, said neck and bearing being separable one from the other.

In testimony whereof I have affixed my signature.

HARRY SLATER.
